Primary Examiner — Karen E Eldridge Powers*(74) Attorney, Agent, or Firm* — Lawrence Cruz, Esq.; Ryan, Mason & Lewis, LLP(57) **CLAIM**

The ornamental design(s) for a hair brush, as shown and described.

DESCRIPTION

FIG. 1 is a perspective view of the hair brush in accordance with the principles of the present disclosure with the first and second members in an approximated condition;

FIG. 2 is a perspective view of the hair brush with the first and second members in an open condition;

FIG. 3 is a right side elevation view of the hair brush of FIG. 1, the left side elevation view being a mirror image thereof;

FIG. 4 is a top plan view of the hair brush of FIG. 1;

FIG. 5 is a bottom plan view of the hair brush of FIG. 1;

FIG. 6 is a front axial view of the hair brush of FIG. 1; and, FIG. 7 is a rear axial view of the hair brush of FIG. 1.

The broken lines shown indicate unclaimed portions of the article and form no part of the claimed design.

1 Claim, 6 Drawing Sheets(56)
